UNITED STATES PATENT OFFICE.

OTTO WOLTERS, OF MAGDEBURG, AND KARL HÖPER, OF BERLIN-CHARLOTTENBURG, GERMANY; SAID HÖPER ASSIGNEE TO SAID WOLTERS.

TYPOGRAPHICAL MACHINE.

Application filed October 1, 1927, Serial No. 223,463, and in Germany October 8, 1926.

This invention relates to a reversing mechanism for typographical machines working with punched registering strips which comprise several magazines.

5 In these magazines different kinds of types can be stored, or the one magazine may contain the small letters and the other magazine the capital letters of the same kind of type. The reversing mechanism is substantially 10 constructed as follows:

Each of the sign- or character-keys is connected by a releasing mechanism, with two escapements controlling the corresponding channels of different magazines. One of 15 these escapements is locked. This locking may be unlocked by the depression of the reversing key, the other escapement being then locked at the same time. Only one of the escapements is released at a time so that only 20 one matrix or element is delivered from the magazine.

In machines, in which the capital and small letters of one kind of type are stored in different magazines, the reversing mechanism 25 requires a separate channel-changing mechanism. In the magazines for the small letters several channels are arranged for certain characters of the alphabet, for instance for the small "e" which happens frequently in 30 the German language. By a suitable changing-mechanism the elements are alternately discharged from the channels so that the channels are uniformly emptied. This changing mechanism may be used also in 35 connection with mono-magazine-machines. When it has to be used for multiple magazine-machines a separate mechanism is necessary 40 for selecting at the reversing a certain channel and for shutting off the other channels.

45 As the capital-letters for instance "E" are less frequently used, only one channel in the second magazine is generally provided for the same. When after the reversing the releasing mechanism would act in the same manner on the second magazine, the elements would be taken also in this case from several juxtaposed channels. As, however, owing to the less great frequency of the capital letters, only one capital-letter-channel corresponds 50 to several small-letter-channels, a separate adjusting mechanism is arranged which releases only the releasing mechanism for the one capital-letter-channel but not those for the other letter-channels. This locking is 55 operated from the reversing key.

The improved reversing mechanism, according to the invention, is shown, by way of example, in the accompanying drawing, in which

Fig. 1 shows in side-elevation the reversing mechanism, the casing being shown in section. 60

Fig. 2 shows the reversing mechanism in elevation, viewed in the direction of the arrow in Fig. 1. 65

Fig. 3 shows constructional details of the channel-changing-mechanism.

Figs. 4a to c illustrate different positions of the safety-mechanism.

All shafts shown in section are journalled 70 in the machine.

At the depression of the key 1 a rod 2 is lifted and an elbow-lever 3 is oscillated. On this elbow-lever rests an eccentric-frame 4, comprising an eccentric 5. When the elbow-lever 3 is oscillated, it releases the edge 4b of the eccentric frame 4 so that this frame can drop, the eccentric 5 being thereby brought into contact with a cylinder 6. The eccentric-frame, oscillatably mounted at the left end 75 on a bolt 4a, is then lifted and lifts the releasing rod 7 controlled by two spiral-springs 7a. The upper end of the releasing rod 7 is suspended on an elbow-lever 8 against which bear the ends of push rods 9 and 10. The other ends of these push-rods bear against 80 escapements 11 and 12 which are rotatably mounted on bolts 11a and 12a. Springs 13 and 14 tend constantly to rotate the escapements and to push thereby to the right the push-rods 9 and 10. 85

When the releasing rod 7 is lifted, one of the push-rods follows the movement of the elbow-lever 8, the other push-rod, for instance 9, being held at its nose 9a by a locking device 95 consisting of a shaft 15 which is, for instance, of semi-circular or semi-circular-ring shaped cross section (Fig. 2). The lower edge 15a of this shaft 15 bears against the noses 9a of all the push-rods 9 arranged the one behind the other, as it extends over the entire width of the magazine, only that push-rod 10 is being released the elbow lever 8 of which 100 has been released by depression of the corresponding sign-key.

When a matrix or element 16 has to be removed from the rear-magazine 17, the magazine 18 must be locked or shut off. With this object in view a reversing key 20 is arranged 105 which, through the intermediary of a lever 110

21, controls a connecting rod 22 which is permanently pulled downward by the action of springs 23. At the depression of the reversing key 20 the rod 22 is pulled downward, whereby a toothed segment 24 is rotated in clock-wise direction. This toothed segment meshes with spur wheels 25, 26 on the shafts 15 and 27. The shaft 27 (Figs. 4a to e) is constructed in a similar manner as the shaft 15 and so adjusted that it liberates the noses 9^a of the push-rods 9 locked by the edge 15^a of shaft 15, while they lock the noses 10^a of the push-rods 10 when those of the push-rods 9 have been released. At the movement of the toothed-segment 24 in clock-wise-direction, the locking of the shaft 15 is suppressed, and the edge 27^a of shaft 27 bears against the noses 10^a of the push-rods 10.

Although the keys 1 are connected with different channels, only one element is liberated at a time by the locking mechanism. The locking is reversed by the depressing of the reversing key so that in this case the element is taken from the second magazine. The reversing mechanism may be constructed in a similar manner for machines with more than two magazines.

At a hasty depression of the reversing key 20 the reversing might be suppressed after one of the sign-keys 1 is being depressed. A separate locking-hook 30 controlled by a spring 31 is therefore provided which, after the rotation of the toothed segment 24 resulting from the depression of the reversing key 20, comes into engagement with a shoulder 32 of the toothed segment 24. As long as the locking hook 30 rests upon this shoulder, the reversing cannot be suppressed again. This can be done only, when the releasing rod 7 of a key 1 is on the return-travel and draws along the bar 33 extending through notches 34 of all the releasing rods 7.

The bar 33 is connected with an elbow-lever 35, on the upper arm of which a pawl 36 is hingedly mounted, which is controlled by a spring 37. The amplitude of oscillation of the elbow-lever 35 may be regulated by an adjustable stop 38 on the casing. The bar 33 is pulled by the action of a spring 33^a, along with the returning releasing rod, and the pawl 36 pulls to the left the lower arm of the locking hook 30 in opposition to the action of spring 31. The locking hook 30 is consequently oscillated by the pawl 36 so that it releases the toothed segment 24 which rotates backward under the action of the springs 33 on the rods 22.

When the reversing key 20 is being depressed when one of the push-rods is still in the working-position owing to the depression of key 1 reversing upon the second magazine might accidentally take place. For this reason the suppressing of the locking on the shaft 15 is retarded at the reversing. With this object in view the toothed wheel

25 is loosely mounted on shaft 15 and connected with the same by a plate-spring 40 (Fig. 4). When the reversing key 20 is being depressed, the spur-wheel 25 is rotated, but shaft 15 is prevented from participating in this movement as a lever 41 is keyed on this shaft which bears against a rotatable abutment 45 on the shaft 27. This abutment 45 moves out of the path of the lever 41 only, when the edge 27^a of shaft 27 has come in front of the noses 10^a of the push rods 10. At this moment the lever 41 is oscillated to the right by the action of the spring 40 which has been put under tension by rotation of the spur-wheel 24, so that the lever 41 rotates the shaft 15. The locking of the push rods 9 is therefore suppressed when the edge 27^a of shaft 27 is lying in front of the noses 10^a of the push-rods 10. When the reversing is suppressed again, the lever 41 slides along the abutment 42 in putting under tension the spring 43 until the abutment 42 is standing again in front of the lever 41.

The channel-changing-mechanism operates in the following manner. To the elbow-lever 3 so many eccentric frames 4 are co-ordinated as juxtaposed channels have to be alternately operated by the depression of the key 1. Only one of these eccentric frames may however be in the working position at a time. With this object in view the eccentric frames 4 have each an extension 50 with a shoulder 51. Locking pawls 52, 52^a, 52^b co-operate with this shoulder. When the front locking pawl 52, as shown in Fig. 1 on the left side, is resting upon the shoulder 51, the abutment 4^b of the eccentric frame 4 rests upon the elbow-lever 3. At the depressing of the key 1 all the elbow levers 3 for the eccentrics are oscillated, only the eccentric 5 coming however into contact with the cylinder 6 so that it is lifted together with its frame 4. A bolt 53 on the extension 50 of the eccentric frame strikes at this occasion against the extension 54 of the next following locking pawl 52^a, which is thus lifted over the shoulder of the corresponding extension of the second eccentric frame. At the oscillating movement of the first eccentric frame the pawl 52 drops, so that it assumes the position shown on the right side of Fig. 1. The second eccentric frame is now in the working position, the first and third frames being locked by the pawls 52 and 52^b so that they do not rest upon the elbow levers 3.

When at the next following depressing of the same key 1 the second frame is lifted, the locking pawl 52 of the same comes into the locking position and the locking of the third frame is suppressed by the lifting of the locking pawl 52^b by means of the bolt 52^a. At the operation of the third eccentric the locking pawl 52^b is lifted which, through the shaft 55, is connected with the locking pawl 52 so that the bolt 53^b brings, by lifting the lock-

ing pawl 54^b, the locking pawl 52 into the position shown on the left side in Fig. 1. A complete change is thereby obtained, one element has been taken from each of three juxtaposed channels of the same magazine by three consecutive depressions of the key 1.

The mechanism as described may be used also in connection with mono-magazine-machines. For the multiple magazine-machine 10 illustrated a separate connection between the reversing mechanism and the channel-changing mechanism must be provided. With this object in view cam-shafts 60 are arranged behind the extensions 50 of the eccentric-frames 4, the cams 61 of said shafts entering not into function before the reversing. At the depressing of the reversing key 20 the cam-shafts 60 are also rotated by a connecting rod 62. The extensions 50^a and 50^b are 15 pushed outward by the cam 61, so that the corresponding eccentric-frames can no longer assume the working position. At the same time the front locking pawls 52 are disengaged by the cams 63 so that, after the depression of the reversing key, the first eccentric-frame rests in the working position on the elbow-lever 3. At the depression of the key 1 only the same eccentric-frame and consequently the same channel of the second magazine 17 is therefore always operated, as long as the reversing-key 20 is suppressed. At the returning of the operated releasing rod 7 the locking of the reversing key is suppressed, so that the channel-changing-mechanism enters again into operation.

When, therefore, the first magazine, in which the small letters are stored, is engaged, one element is discharged alternately from several juxtaposed channels at the depression 20 of the key 1. The eccentric-frames control themselves mutually so that the frame in movement suppresses every time the locking of the following frame in order that the same comes into the working position. When a 25 reversing is carried out, this changing mechanism is automatically put out of operation, and at the depression of the key 1 only one and the same escapement of the same channel in the second magazine is always operated so that the capital-letter-element is taken only from one channel.

We claim:—

1. A reversing mechanism for typographical machines with several magazines comprising in combination two transverse push-rods, a nose on each push-rod, a locking shaft of semi-circular cross-section adapted to lock the noses of said push rods, escapements one for each magazine springs controlling said escapements, and an intermediate lever against which said push rods are pressed by the action of said springs.

2. A reversing mechanism as specified in claim 1, in which transverse push-rods are arranged, a nose on each push-rod, escape-

ments one for each magazine springs controlling said escapements, and a movable locking mechanism against which said push rods noses are pressed by the action of said springs.

3. A reversing mechanism as specified in claim 1, comprising in combination with a reversing key and with a releasing mechanism comprising push rods a movable locking mechanism consisting of two shafts of semi-circular cross-section, a spur wheel on each shaft, a toothed segment, connected with said shafts by means of said spur wheels, means for rotating said toothed segment from said reversing key so that at every operation the front-edge of one of said shafts bears against the noses of one group of said push-rods.

4. A reversing mechanism as specified in claim 1, comprising in combination with the reversing key the releasing mechanism comprising push-rods and a releasing rod, a locking mechanism, a locking hook which after depression of said reversing key locks the locking mechanism in its position, and a catch bar controlled by said releasing rods and which at the depressing of the reversing key is operated by one of said releasing rods at the return movement and releases said locking hook from its locking position.

5. A reversing mechanism as specified in claim 1, comprising in combination with the magazines, a locking mechanism, comprising a shaft, a spur-wheel, loosely mounted on said shaft, a plate-spring connecting said spur-wheel with said shaft, an arm on said shaft, a second shaft, and an abutment on said second shaft designed to bear against said arm for retarding the movement of said shaft at the reversing.

6. A channel-changing mechanism for the reversing mechanism as specified in claim 1, comprising in combination with a key-board and with releasing mechanisms for several channels of the same magazine, eccentric-frames co-ordinated to one key, an extension of each eccentric frame, a locking nose on each extension, an abutment on each extension and a shoulder on each extension said extensions operating in such a manner that the extension of the actually operated eccentric frame lifts by its abutment the locking nose of the next following extension over the shoulder of the next following extension to release the same.

7. A channel-changing mechanism for the reversing mechanism as specified in claim 1, comprising in combination with a reversing key, a releasing mechanism for said channel as changing mechanism which brings by abutments into working position the releasing mechanism for the channel co-ordinated to the same sign-key as the channel-changing mechanisms and locks at the same time the changing mechanism.

8. A channel-changing mechanism for the

reversing mechanism as specified in claim 1, comprising in combination with a reversing key a releasing mechanism for said channel as changing mechanism which brings by abutments into working position the releasing mechanism for the channel co-ordinated to the same sign-key as the channel-changing mechanisms and locks at the same time the changing mechanism, and comprising in combination with the eccentric frame and the extensions of said frames, cam-shafts behind

said frame extensions and connected to said reversing key, cams on said shafts for locking at the reversing the extensions of the eccentric frames of those channels which are not co-ordinated to the same sign-key and move out of the locking position the locking noses of the other extensions. 15

In testimony whereof we affix our signatures.

OTTO WOLTERS.

KARL HÖPER.
